UNITED STATES PATENT OFFICE.

PHILIP F. PILLINER, OF PHILADELPHIA, PENNSYLVANIA.

VALVE-SPRING COMPRESSOR.

1,045,321.

Specification of Letters Patent. Patented Nov. 26, 1912.

Application filed July 20, 1912. Serial No. 710,586.

To all whom it may concern:

Be it known that I, PHILIP F. PILLINER, a citizen of the United States, residing at Philadelphia, in the county of Philadelphia and State of Pennsylvania, have invented 5 certain new and useful Improvements in Valve-Spring Compressors, of which the following is a specification.

My invention relates to improvements in 10 valve spring compressors, the object of the invention being to provide an improved tool which may be conveniently handled and which will most effectually compress the spring of engine valves, and hold the 15 same compressed to allow the key to be easily removed and replaced.

A further object is to provide a device of 20 this character which may be adjusted so as to give the members the necessary amount of movement, and provide means for holding the members with the spring compressed.

With these and other objects in view, the 25 invention consists in certain novel features of construction and combinations and arrangements of parts as will be more fully hereinafter described and pointed out in the claims.

In the accompanying drawings: Figure 1 30 is a view in elevation illustrating my improvements in operative position. Fig. 2 is a fragmentary view in vertical section through the valve spring and collar plate showing the position of my improved tool 35 thereon. Fig. 3 is a fragmentary elevation at right angles to Fig. 1 showing the position of the lower member of my improved tool on the valve roller holder adjusting screw. Fig. 4 is a view in section 40 on an enlarged scale on the line 4—4 of Fig. 1. Fig. 5 is a plan view of one of the tool members. Fig. 6 is a view in elevation at right angles to Fig. 1 showing the tool 45 partly in section. Fig. 7 is a view in elevation of the adjusting nut. Fig. 8 is a view in section on the line 8—8 of Fig. 6, and Fig. 9 is a plan view of the other tool member.

My improved valve spring compressor 50 comprises two members 1 and 2. The member 1 is provided between its ends with a bifurcated bracket 3 in which a screw-threaded rod 4 is pivotally secured by means of a rivet 5. This screw 4 is positioned 55 through openings in an enlargement 6 on member 1, and this enlargement 6 is pro-

vided with a slot 7 in which a thumb nut 8 is located. This thumb nut 8 engages the threads of rod 4, and as the thumb nut is of appreciably greater diameter than the 60 enlargement it can be readily turned to adjust the members toward and away from each other. Both members 1 and 2 have handles 9 and 10 respectively which afford a ready grip for the hand. The opposite 65 end of member 1 is of general U-shape as shown at 11 forming a relatively wide fork, said fork at its ends on its inner face is provided with inwardly projecting shoulders 12 which are adapted to engage the valve 70 spring collar plate 13. The end of member 2 is provided with a fork 14 which is adapted to straddle the valve roller holder adjusting screw 15 between the head thereof, and the ordinary check nut 16 located 75 thereon.

In Fig. 1 I illustrate my improvements in connection with an ordinary spring held valve such as commonly employed on engines of the internal combustion type. 17 represents the valve and 18 the stem having the ordinary coiled spring 19 around the same, exerting pressure against the collar plate 13, and this collar plate 13 held on the stem by means of the key 20, which is projected 80 through a slot in the stem and limits the movement of the plate. As is customary with plates of this kind, they are dished or recessed centrally so that it requires considerable movement of the plate on the stem 85 to release the key. With my improvements, it is a simple matter to move the plate on the key, because when the parts are in the position above explained, a pressure on the handle end of the two members will move 90 the plate on the stem, and the plate may be held in this position by means of a bail 21. This bail 21 is pivotally connected to a lug 22 on member 1, and is adapted to receive and hold the handle 10 of member 2. In 100 other words, after the spring is compressed, the bail may be slipped over handle 10, and the spring will be effectually held in this position so as to allow the key to be readily removed.

The lugs 12 on the forked end 11 have curved upper faces so that they readily position themselves regardless of the angle of member 1.

By adjusting the nut 8, the fulcrum point 110 of the levers will be moved, so that any necessary movement may be given the mem-

bers to compress the spring and release pressure on the key. The device may be quickly placed in position on any ordinary valve mechanism, and may be easily operated by any one of average intelligence to quickly remove and replace the key.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A valve spring compressor comprising two members, a rod spacing the members apart pivotally connected to one member, and adjustably connected to the other member, and said members constructed to engage a fixed part and the spring collar plate respectively of an engine valve structure, substantially as described.

2. A valve spring compressor comprising two members, a threaded rod spacing the members apart pivotally connected to one member between the ends of the latter, a thumb nut adjustably connecting the rod with the other member, and one end of each member forked, substantially as described.

3. A valve spring compressor comprising two members, an adjustable fulcrum device connecting the members between their ends, said device spacing the members apart and comprising a rod pivotally connected at one end to one member and adjustably con-

nected at its other end to the other member, both members, having one forked end, the forked end of one member wider than the other, and inwardly projecting lugs on the larger forked member, substantially as described.

4. A valve spring compressor comprising two members, an adjustable fulcrum device connecting the members between their ends, said device spacing the members apart and comprising a rod pivotally connected at one end to one member and adjustably connected at its other end to the other member, both members having one forked end, the forked end of one member wider than the other, inwardly projecting lugs on the larger forked member, a bail pivoted to one member and adapted to engage over the other member, substantially as described.

5. A valve spring compressor comprising two members, a threaded rod pivotally connected to one member, the other member having openings through which the rod is positioned, and also having a slot intersecting the openings, a thumb nut in said slot engaging the threads of the rod, whereby the members may be adjusted toward and away from each other, and said members constructed to engage a fixed part and a collar plate respectively, substantially as described.

In testimony whereof I have signed my name to this specification in the presence of two subscribing witnesses.

PHILIP F. PILLINER.
